UNITED STATES PATENT OFFICE.

JOHN B. GOHMANN, OF LINCOLN, NEBRASKA.

AIR-PURIFYING APPARATUS.

1,418,296.

Specification of Letters Patent. Patented June 6, 1922.

Application filed March 7, 1921. Serial No. 450,444.

To all whom it may concern:

Be it known that I, JOHN B. GOHMANN, a citizen of the United States, residing at Lincoln, in the county of Lancaster and State 5 of Nebraska, have invented certain new and useful Improvements in Air-Purifying Apparatus, of which the following is a specification.

My invention relates to means for purifying and moistening the air supplied to rooms, apartments or other spaces in conjunction with means for heating the air, or otherwise used, and its object is to provide for greater efficiency of operation as well as 15 a simple, reliable and durable structure in devices of this character.

My invention consists in the combination of parts and in the details of construction and arrangement of parts as will hereinafter be more fully described and claimed.

In the drawing:

Fig. 1 is a general perspective view of an apparatus embodying my invention installed in conjunction with a furnace for heating 25 the air and inducing its circulation through my apparatus, and showing different parts of the apparatus adjusted to various positions:

Fig. 2 is a partial perspective view similar to Fig. 1, but showing all of the parts adjusted into similar positions:

Fig. 3 is a vertical longitudinal section on a plane corresponding to the line 3—3 of Fig. 2 and enlarged;

Fig. 4 is a partial sectional elevation corresponding to Fig. 3, but showing a modification of the water-supply means:

Fig. 5 is a sectional detail of one of the pans, the section being on a plane corresponding to that of Fig. 3, but showing a modification of the pan, parts of which are omitted for lack of space:

Fig. 6 is a partial transverse section showing how the pans are adjustably mounted in 45 the casing:

Fig. 7 is a vertical section showing another embodiment of the invention:

Fig. 8 is an enlarged cross-section on the line 8—8 of Fig. 7, and

Fig. 9 is a vertical section showing an air washer for steam or hot water radiators.

My invention is especially intended for use in conjunction with hot-air furnaces, although it will be understood that it may 55 be utilized independently of such furnaces. Therefore the illustration of its use in con-

junction with the furnace 1 in Fig. 1 is merely illustrative. As here shown, the furnace 1 comprises the interior combustion-sustaining means 2 from which a pipe 3 leads for the outlet of products of combustion; with a casing 4 to compel the passage of air close to the means 2 for heating, from which the heated air passes out through the hot-air pipes 5 to the rooms or other spaces 65 to which the heated air is to be supplied.

When used in this conjunction, my improved apparatus comprises the casing 6 joined onto one side of the furnace-casing 4 and being preferably of box-like formation 70 with a flat top 7 and sides 8. It preferably extends up somewhat more than half the height of the furnace casing 4 to the flat back 9 to which it is joined, and which back 9 thus forms the front of the air-washer 75 casing; being, however, cut away at the bottom leaving the air-intake opening 10 from the air-washer casing into the furnace casing.

The front of the air-washer casing is 80 open, and on the inner surfaces of the sides 8 are ledges 11 extending horizontally from front to rear at intervals from the tops to the bottoms of the sides. Supported on these ledges 11 are the pans 12 each of shallow rectangular formation and so proportioned as to slide easily into the air-washer casing on these ledges and be adjusted to any desired position forwardly or rearwardly thereof, as indicated in Fig. 1 where 90 the pans are shown adjusted to various positions, each lower pan extending farther out to the rear than the next one above it.

It is the function of these pans 12 to hold water so that the air passing through the 95 air-washer casing into the furnace-casing, as induced by the heating of the air in the furnace casing, will sweep across the surface of this water and part with impurities; as well as absorb some of the water; so that when 100 the air passes up through the hot-air pipes 5 into the space in the room, or other space, the air will have the right degree of purity and humidity.

For the purpose of permitting the free 105 passage of air across each surface of water, the pans are spaced apart such distances as to afford the correct total cross-section to the passage through the washer-casing; and the pans are made of such length from front 110 to rear of the casing that the air coming to the front of the casing from the various pas-

sages 13 thus left over the pans 12 will enter a downward passage 14 of ample cross-section to conduct all of the air from the passages 13 above the level of the top of the air-intake 10 of the furnace casing 4 and the lower front of the air-washer casing, as before described. The air from those passages 13 below the level of this top will, of course, pass directly in through the opening 10.

16 Adjusting the pans forwardly or rearwardly in the casing, as illustrated in Fig. 1, somewhat affects the operation of the device, in that it affords lateral inlets to the rear parts of the passages 13 as well as of the inlet; thus facilitating the entrance of the air and reducing the enclosed length of each passage 13 and thereby reducing somewhat the resistance to the passage of the air through the washer, as well as reducing the amount of water surface to which the air is effectively confined during such passage. Thus, the degree of humidity may be somewhat controlled by such adjustment. Moreover with the pans thus slidably mounted 25 in the casing, each one is readily removed for cleaning or repair.

As the water is evaporated during the operation of the device, it is highly desirable to have a convenient means for replenishing the water in the various pans. I prefer to do this by providing each pan 12 with an outlet 14^a in its bottom having a raised rim 15 but slightly lower than the rim 16 of the pan (Fig. 3.) This outlet is located away 30 from the center of the pan, and with their outlets thus located, the pans are variously placed in the casing so that the outlet of each pan will be out of line with the outlet of the pan immediately above it, as shown 35 in Fig. 3. It will be understood that all of the pans may be made alike, even as to this relative location of the outlet 14^a; and that this displacement of the outlets of adjacent pans may be effected by putting each 40 alternate pan into the casing backwards.

With the pans thus provided with the outlets 14^a, if water is supplied to the uppermost pan it overflows the lower rim 15 of the outlet 14^a before it reaches the higher rim 50 16 of the pan; and the water overflowing passes to the next lower pan which overflows in the same manner to the pan below it, and so on until each one of the pans is filled to the height of the rim 15 of its respective outlet or overflow passage 14^a.

A basin 17 is provided below the casing, as here shown being formed in the floor 18, and the overflow from the lowermost pan 60 12 passes into this basin 17, which basin in turn is provided with an overflow outlet 19 which may lead to a sewer or other means to dispose of the water that finally overflows. This basin 17 preferably extends forward into the furnace-casing 4, and the water in 65 the basin, of course, has its surface swept by

the incoming air and acts upon the air and is evaporated thereby the same as the water in each pan 12.

It is highly desirable that these pans should be kept supplied with water at all 70 time while the furnace or other air-supplying means is in use in conjunction with my apparatus.

As shown in Fig. 1, there is a water-supply pipe 20 leading back from the furnace 2 75 where it is connected to the water-heating apparatus in the furnace, which, being well understood, need not be illustrated or described herein, and opening through a faucet 21 into the upper-most pan of my apparatus. Such a faucet 21 may be manipulated by hand to lead water into the pans when needed. But this, of course, implies that one will watch the apparatus closely to see when the water is needed, and also if the faucet 21 be left open too long too much water will be supplied and will merely flow out through the overflow outlet 19 of the basin 17 and be wasted. The advantage of employing steaming hot water is that a 90 more effective purifying action is obtained, all dust, lint, germs and foul odors being arrested and separated from the air.

As shown in Fig. 3, the pipe 20 has interposed in it a valve 22 with a vertically sliding plug 23 having the upper end of the rod 24 connected to it, and the lower end of the rod being connected to a lever 25 having a fulcrum 26 on the side of the casing forwardly of the rod 24, and having at its free rear end a float 27 resting on the water in the basin 17. The parts are so proportioned as to size and weight that as long as the water is at a desirable level in the basin 17, the plug 23 will be held up to its seat in the valve 22 and no water can pass this valve; but as the level of the water falls in the basin 17, the plug 23 will be pulled down away from its seat by the weight of the parts and open valve 22, and the faucet 21 100 having been left open, water will pass into the uppermost pan 12. It being necessary for the float 27 to be raised before the valve 22 will be closed, and the necessary rising of the water in the basin 17 being dependent upon overflow of all of the pans 12, it follows that all of the pans will be filled to overflowing before the valve 22 begins to be closed, and the basin 17 will, of course, be filled to overflowing by the time the valve 110 22 is closed. The operation of the device with the float in the basin 17 will be satisfactory if enough fall of water in the basin 17 to open the valve 22 takes place before the water in any one of the pans 12 is entirely 115 exhausted, it being understood that the need is to have the required exposed surface of water in each one of the pans at all times, regardless of the particular depth of the water in the pan.

125

130

As shown in Fig. 4, the water-supply pipe 20' enters at the bottom of the casing and may lead directly from a water main and supply cold water to the apparatus, or may 5 lead in this way from the heating apparatus. However this may be, when the pipe thus enters at the bottom it has the valve 22' at the bottom of the apparatus with the lever 25' having its fulcrum 26' directly on the 10 valve body and its float 27' resting on the surface of the water in the basin 17, as in the preceding example. The pipe 20' leads up and discharges into the uppermost pan 12'; and, as here shown, is not provided with 15 any faucet 21. It will be understood that the faucet 21 may be used with the automatic valve 22 or 22', or may be omitted when either one of these valves is provided; or, if automatic governing of water supply is 20 not to be used, the faucet 21 may be used alone, as shown in Fig. 1.

The overflow passage with its raised rim in each pan may be provided by forcing the metal of the pan up around an opening in 25 the bottom thereof, as shown in detail in Fig. 5 where the passage 14' is through the raised parts of the metal with its rim 15' somewhat below the rim 16' of the pan 12'.

In the embodiment of the invention as 30 disclosed in Figs. 7 and 8, the water pans are so constructed and arranged that the casing 6 may be eliminated, thereby simplifying and cheapening the apparatus. Each pan comprises a bottom 28, end walls 29 35 and side walls 30. It will be noted that the side walls are somewhat higher than the end walls, and near their top edges they have inturned flanges or ledges 31.

Several pans constructed as hereinbefore 40 described are employed; they being placed in superposed and spaced relation, and they are supported in this way by seating a pan on the ledges 31 of the next pan below. Inasmuch as the ledges 31 are above the plane 45 of the top edges of the end walls 29, it will be evident that there is left a space between the bottom and the open top of each two adjacent pans, so that the air may enter this 50 space and pass across the surface of the water in the pans.

The stack of pans is so arranged with respect to the air intake opening 10 of the furnace casing 4, that the rear low ends of the pans face said opening; leaving the high 55 sides of the pans at the sides of the stack. It will therefore be seen that the stack of pans forms a series of narrow air passages to the intake 10, and the air in passing through these narrow spaces, and across the surface 60 of the water in the pans, is relieved of its impurities and is also humidified. To assist in holding the pans in superposed relation they are also provided with props 32 rising from the bottom thereof to the height of the 65 flanges 31. These props do not extend

throughout the entire width of the pan and hence they do not obstruct the flow of water to all parts of the pan. The flanges 31 are slightly below the top edges of the walls 30, and the pans seat inside the latter, whereby 70 they are prevented from shifting laterally.

The pans may also be provided with a bottom overflow 33 into the pan below operating in the same manner as the overflow means previously described. The overflow 33 may be a tube rising to a height slightly less than that of the walls 29, or they may be formed by an apertured raised portion of the pan bottom. The pan at the bottom of the stack has no overflow, and it rests directly on the 80 floor or other supporting surface.

At the top of the stack of pans is a lid or cover plate 34 supported by the furnace casing 4.

The supply of water for the pans is obtained by a pipe 35 connected to the water heating apparatus of the furnace, and leading to a funnel 36 supported by the plate 34 to discharge into the top pan. The pipe 35 is provided with a valve 37 for controlling 90 the flow of water to the pans. It will be understood that the apparatus may also be provided with the automatic valve control hereinbefore described.

Fig. 9 shows the apparatus applied to a 95 steam or hot water radiator 38. Over the radiator is placed a hood 39 reaching down to within a short distance of the floor so that air may enter at the bottom, the top of the hood having air escape openings 40 and 100 being spaced from the top of the radiator a sufficient distance to enable the water pans 41 to be positioned in the hood above the radiator. The pans are supported within the hood in spaced and superposed relation 105 as before, and a valved water supply pipe 42 enters the hood to discharge into the top pan. All the pans, except the bottom pan have overflows as before, and the bottom pan is fitted with a gage 43 so that the water 110 level may be observed, said gage being positioned on the outside of the hood. Beneath the top of the hood is a baffle plate 44 to deflect the air across the top pan.

The entire assembly of hood and pans is 115 removable from the radiator for cleaning.

I claim:

1. In an air-washer, a casing, an upright series of shallow containers in said casing spaced apart with passages between the containers for the passage of currents of air in parallel over the surfaces of bodies of water held in said containers, one side of said casing being open to admit said currents of air, and the other side of said casing being open 120 for the escape of said currents of air, each one of said containers being slidably mounted in said casing, whereby it may be adjusted to project from the first mentioned open side of the casing.

2. In an air-washer, a series of water pans arranged in superposed relation, said pans having opposite side walls which are higher than opposite end walls, and said side walls having ledges to seat the pan next above in the series, said ledges being below the top edges of the side walls and above the plane of the top edges of the end walls. 5
  3. In an air-washer, a series of water pans arranged in superposed relation, said pans having side walls which are higher than opposite end walls, and means for supporting the pans on each other with their bottoms spaced from the end walls of the pan below. 10
  4. In an air-washer, a series of water pans arranged in superposed relation, said pans having side walls which are higher than opposite end walls, and means on the side walls for supporting the pans on each other with 15 their bottoms spaced from the end walls of the pan below. 20
  5. In an air-washer, a series of water pans arranged in superposed relation, said pans
- having side walls which are higher than opposite end walls, and means on the side walls 25 for supporting the pans on each other with their bottoms spaced from the end walls of the pan below, and for closing the spaces between the pans at the sides of the series.
6. In an air-washer, a series of water pans 30 arranged in superposed relation, said pans having side walls which are higher than opposite end walls, and means for supporting the pans on each other with their bottoms spaced from the end walls of the pan below, 35 and for closing the spaces between the pans at the sides of the series.
7. In an air-washer, a series of water pans, and means on said pans for supporting the same on each other in spaced superposed relation, with the spaces between the pans closed at the sides of the series and open at the ends of the series. 40

In testimony whereof I affix my signature.

JOHN B. GOHMANN.
